UNITED STATES PATENT OFFICE

HOBART M. MYRACLE, OF OKLAHOMA CITY, OKLAHOMA, ASSIGNOR TO AMERICAN IRON AND MACHINE WORKS COMPANY, OF OKLAHOMA CITY, OKLAHOMA, A CORPORATION OF OKLAHOMA

PIPE CUTTER

Application filed January 19, 1931. Serial No. 509,865.

My invention relates to pipe cutters and more particularly to a device of that character for severing a string of drill pipe or well casing to permit salvaging of a portion of the string when it is impossible to remove the entire string from the well due to caving or other causes.

Cutters heretofore employed have been equipped with two blades and the use of this structure results in binding and chattering of the blades and uneven cutting of the pipe, due to a departure of the cutting device from concentric relation with the pipe.

The principal object of my invention, therefore, is to provide a cutter that will automatically maintain a position concentrically within the pipe due to the particular mounting and number of cutter blades employed, thereby insuring a rapid and uniform cutting operation.

A further object of the invention is to provide a simple device, constructed of parts that may be easily assembled and readily replaced when worn or broken.

In accomplishing these and other objects of the invention, I have provided improved details of structure, the preferred form of which is illustrated in the accompanying drawing, wherein:

Fig. 1 is a central vertical section through a cutter in cutting relation with a drill pipe, the guide member for the cutter being shown in elevation.

Fig. 2 is a similar sectional view illustrating the drill pipe completely severed and the cutter blades withdrawn into their housing for withdrawal from the drill pipe.

Fig. 3 is a perspective view of the several cutter members in spaced relation.

Referring more in detail to the drawing:

1 designates a string of drill pipe consisting of tubular sections joined together by threaded coupling members 2 and 3 having aligning reduced bores 4.

The cutter embodying my invention and generally designated 5, is preferably secured to the externally threaded lower end 6 of a string of well tubing 7 by a coupling 8 having upper and lower internally threaded sockets 9 and 10 for respectively receiving

the lower end of the tubing and the upper end of a tubular body member 11 of the pipe cutter.

The body member is preferably provided with a reduced threaded neck 12 for seating in the lower socket 10 of the coupling so that the outer periphery of the body member will be flush with the outer face of the coupling and with the outer face of a pilot or guide member 13 secured to the internally threaded lower end 14 of the body member by a reduced externally threaded neck 15. The aligning outer walls of the coupling, body and guide members permit the device to pass readily through the bores 4 of the couplings, entrance into the couplings being facilitated by a rounded lower end 16 of the guide member.

A further reduced continuation of the neck 14 comprises a head 17 having a plurality of inclined notches 18 for directing cutter blades 19, presently more fully described, through aligning lateral slots 20 formed in the wall of the body member.

Provided in the coupling 8 is a constricted bore or guide opening 21 for slidably receiving an actuating stem 22 having a plurality of flat faces 23 on its lower end, each provided with a laterally extending bearing pin 24 for pivotally mounting one of the cutter blades 19.

The cutter blades are preferably of arcuate form, tapering to a cutting edge 25, so that their curved faces 26 will slidably engage the inclined faces of the notches 18 to direct the cutting ends of the blades at substantially right angles into engagement with the casing wall.

In order to normally retract the cutter blades into the body member, a spring 27 is mounted over the actuating stem and is seated in the upper socket 9 of the coupling 8, being retained therein by a piston 28 secured to a reduced threaded end 29 of the stem by a washer 30 and nut 31.

Various means may be employed for limiting retractive movement of the stem, but I have provided for this purpose an enlarged portion 32 adjacent the lower end of the

stem to form a stop shoulder 33 for engaging the coupling 8.

Assuming a device to be constructed and assembled as described, the operation for cutting a pipe in a well would be as follows:

The cutter, after being assembled, is attached to the lower end of the tubing and is lowered into the casing until the guide 13 enters the body of a coupling member 10 near the point where the casing is to be severed. Fluid pressure is then admitted into the tubing to compress the spring and urge the actuating stem downwardly into the body member to project the cutter blades into engagement with the inner wall of the pipe.

The tubing is then rotated and pressure is continuously applied to the piston in the tubing in such amounts as required until the blades have severed the drill pipe. Upon release of pressure from the tubing the spring elevates the piston within the tubing, thereby retracting the blades within the body member, as disclosed in Fig. 2, and permitting removal of the tubing and cutting device from the pipe.

I prefer to employ three blades, as shown in the drawing, the principal purpose of which, being that the equal spacing of three blades will tend to produce a uniform radial pressure on the body member, thus maintaining concentric relation of the lower end of the body member with the pipe.

What I claim and desire to secure by Letters Patent is:

1. An internal cutter for a cylindrical member, a tubular body member having three lateral slots, an extended guide member threaded into the lower end of said body member, a head on the guide member extending upwardly into the body member, said head having notches in its end respectively aligning with said slots, a stem reciprocably mounted in the body member, three cutters pivotally mounted at one end on the end of said stem, the opposite ends of said cutters being provided with cutting edges and adapted to engage said notches to be directed through the slots upon downward movement of the stem in the body member and have their cutting edges brought into cutting engagement with the interior of the cylindrical member and also maintaining said body member in concentric relation to said cylindrical member, and means for normally retracting said cutters into the body member.

2. An internal cutter for a well casing joined by couplings having constricted bores, a tubular body member having three lateral slots, a guide member associated with the body member and adapted to engage a bore of a coupling, said body member and guide member having equal outside diameters, a head on the guide member extending upwardly into the body member, said head hav-

ing notches respectively aligning with said slots, a stem reciprocably mounted in the body member, three cutters pivotally mounted at one end and provided with cutting edges on their opposite ends on the lower end of said stem, said cutters adapted for engaging said notches and to be directed through the slots upon downward movement of the stem in the body member, thereby bringing said cutting edges into engagement with said well casing for cutting the same, said cutters also preventing lateral movement of said tubular member, means for normally retracting said cutters into the body member, and stop means on the body member and stem for limiting retractive movement of the stem.

In testimony whereof I affix my signature.

HOBART M. MYRACLE.
